EXPLOSION-PROOF ENCLOSURE FOR CENTRIFUGES AND THE LIKE

Charles J. Filz, Weston, Conn., assignor to Ivan Servall,
Inc., Norwalk, Conn., a corporation of New York
Filed July 11, 1960, Ser. No. 41,952
6 Claims. (Cl. 74—609)

This invention relates to explosion-proof enclosures for centrifuges and the like, and more particularly to improved structural arrangements therefor.

In operating laboratory or industrial centrifuges, there is an ever present hazard, as a result of high and ultra high speed rotation, that structural defects may cause the rotor to fracture whereby its fragments would be hurled about at ballistic speeds around the laboratory with serious personal and property damage as a consequence. Various protective enclosures have heretofore been utilized; in most cases, however, a compromise had to be made as to the wall thickness and weight since it was apparent that there were limitations in cost and size beyond which it was not feasible to go. Accordingly, previous enclosures, that were purportedly explosion-proof, have not offered the best type of security that is desired in a laboratory.

Accordingly, the present invention concerns itself with providing an explosion-proof enclosure, which, while it is made of a strong steel container, is not necessarily so thick in its wall cross section that it is unwieldy or too costly; at the same time various structural arrangements are incorporated whereby the container walls are prevented from being torn by the impact of parts hurled at projectile speed from a broken or exploded centrifuge rotor. The walls of the explosion-proof chamber of the present invention are arranged to yield under the impact of rotor fragments and to absorb their force under the release of shear bolts, while at the same time the complete collapse or fracture of said walls is prevented by novel interlocking and anchoring arrangements which ensure the integrity of the enclosure around a fracturing or exploding centrifuge rotor.

By this means the present invention obviates the necessity for surrounding the explosion-proof apparatus with a cabinet as a so-called second line of defense as has been necessary with heavy rigid apparatus of the prior art, where little or no yieldability was present in the wall structure.

Still other objects and advantages of the invention will be apparent from the specification.

The features of novelty which are believed to be characteristic of the invention are set forth herein and will best be understood, both as to their fundamental principles and as to their particular embodiments, by reference to the specification and accompanying drawings, in which:

FIGURE 1 is an enlarged section view, taken on line 1—1 of FIG. 2, some parts being broken away and some parts being shown in elevation and phantom outline;

FIG. 2 is a greatly reduced top view of the apparatus shown in FIG. 1, some parts being broken away; and

FIG. 3 is a slightly reduced view taken on line 3—3 of FIG. 1, some parts being omitted, some parts being broken away.

Referring now to the drawings in detail, the explosion-proof enclosure, generally, designated 11, comprises a unitary, vertically extending, circular, steel wall or housing 12 which defines an explosion chamber 13 within which a centrifuge rotor 14 is concentrically positioned. Rotor 14 may be generally of the size illustrated, or it may be the size indicated in the dashed outline 15, as shown in FIG. 1. Rotor 14 is mounted on a drive shaft 16, the lower end of which is connected by suitable means

2

to a motor, not shown. Shaft 16 is surrounded by a shaft housing 17 which is connected to a mounting ring 18 which forms the support for a motor or the like.

An integral part of a structural base, cabinet, frame or the like, not shown, is the horizontal plate 21 which has a central circular aperture bounded by an annular lip 22 which cooperates with an annular recess 23 in ring 18, to form a secure connection therebetween. Attached to an outer portion of the top surface of base plate 21 by means of a plurality of shear pins or bolts 25 in circular array is a horizontal, steel anchor ring 26.

Base plate 21 has an upwardly extending ring-like boss 27 to the top horizontal surface of which is secured a circular steel retaining plate 28 by means of bolts 29. Both boss 27 and plate 28 have central apertures to provide clearance for mounting ring 18. Retaining plate 28 has a substantially larger diameter than boss 27 whereby the outer peripheral portions of said plate are spaced apart from the top surface of base plate 21. That peripheral portion of retaining plate 28 which extends over a circular portion of anchor ring 26 is spaced apart vertically from the latter.

Connected to the top of retaining plate 28 by means of screws 31 is a ring 32 to the top of which is connected a stiff but somewhat resilient collar 33 made of rubber, neoprene, or the like, the inner portion of said collar being apertured and having a flexible, annular lip 34 which frictionally engages the peripheral surface of shaft housing 17 thereby sealing chamber 13 from deleterious materials or air currents that might otherwise enter said chamber.

The annular bottom edge of housing 12 is rigidly secured to the peripheral portion of anchor ring 26 by means of a strong welded annular joint 37. The inside diameter of housing 12 is somewhat greater than the peripheral diameter of retaining plate 28. Positioned between the periphery of retaining plate 28 and the inner wall of housing 12 and resting on the top surface of ring 26 is a ring 38 made of a suitable resilient material, such as rubber, neoprene or the like, and in order to form an air and liquid seal, and to act as a sound absorbing medium.

The outer periphery of the upper portion of the wall of housing 12 has a horizontal annular recess 41 above which said wall is formed in an integral outwardly extending circular lip 42.

The open top of housing 12 is enclosed by a circular convex steel cover 43 which may be provided at its apex with a central aperture 44. Cover 43 has a downwardly extending circular side wall 45 which terminates in an inwardly extending annular lip 46.

Hinge element 47 is firmly secured to cover wall 45 while hinge element 48 is firmly secured to the side of housing 12, said two hinges being interconnected by pin 49 whereby cover 43 is mounted pivotally in respect of said housing. Cover 43 is secured in position on top of housing 12 by means of one or more suitable locking arrangements, each comprising, for example, a hook 50 connected by means of bracket 51 to the outer surface of housing 12 and which is engaged by a latching loop 52 connected to a pivoting latch 53 connected to bracket 54 mounted on cover wall 45. Latch 53 has an upwardly extending handle 55 which provides for manual operation of the latching device.

It will be noted from FIG. 1 that lip 46 of cover 43 rests upon the outer portion of the bottom of recess 41, and that the vertical dimension of lip 46 is somewhat smaller than the vertical dimension of recess 41. Also, the inner edge of lip 46 is spaced apart from the inner vertical wall of recess 41.

In the case of a fifteen pound centrifuge rotor running at 20,000 revolutions per minute, for example, it would

ordinarily be necessary to provide an explosion container whose steel walls and cover are in the order of 1½" thick to provide for reasonable safety. Such a container is a fairly massive structure and would be unwieldy for use on the ordinary laboratory table. If the wall and cover were made somewhat thinner, it would then be necessary to provide an auxiliary cabinet around the chamber in order to provide a so-called second line of defense against the possible rupture of such thinner wall.

By employing the safety features embodied in the structural arrangement of the present invention, it is possible to reduce the wall thickness of the present explosion chamber to the order of 5/8", and the cover to the order of 1/4" thick.

In the event of an accidental explosion or fracture of the rotor (14 or 15) while the latter is rotating at high speed, fragments hurled therefrom at ballistic or projectile speeds and impinging upon the wall 12 of enclosure 11 will cause said wall, or at least a portion thereof, to become distorted. In the case of moderate impacts, wall 12 would retain its generally vertical position by virtue of bolts 25 holding anchor plate 26 down on its plate 21. In the event of a drastic explosion, such as would take place when a rotor fractures in two pieces, the impact upon wall 12 would be so great as to cause the outward motion of wall 12 to the point where the force of the impact overcomes the predetermined shear resistance or limit of shear bolts 25, whereby anchor plate 26 will be released or freed from base plate 21. By means of this releasing action of shear bolts 25, the outward movement of wall 25 provides a shock absorbing action for the impact of the fragments, whereby the accident is contained within chamber 11. As a further insurance factor to contain the accident within the chamber, retainer plate 28 limits the pivotal motion of anchor plate 26 and, accordingly, of wall 12 in order to prevent their complete dislocation from base 21.

A further safety factor inherent in the structure illustrated and described herein is provided by the engagement or interlocking action between lip 46 of cover 43 and recess 41 of wall 12. Since the inner edge of lip 46 is initially spaced apart from the inner vertical surface of recess 41, it can be seen that wall 12 is permitted a certain amount of yieldable outward movement as a result of the rupture of shear bolts 25, which permits said wall to absorb the impact of fragments flying from the fractured rotor. Such outward movement is limited or stopped when lip 46 becomes interlocked with recess 41. The interengagement between lip 46 and recess 41 as a result of impacts upon wall 12 automatically locks cover 43 securely on the apparatus and serves to contain the flying fragments within the chamber. Since wall 12 has a modicum of ductility, the intermediate portion between the top and bottom edges thereof may bulge outwardly under the impact of high speed fragments. This bulging action further helps to contain the explosion within the chamber and keep the fragments ricochetting only into the interior of the chamber.

By virtue of the structures disclosed herein, there are multiple factors of safety incorporated by simple means into the explosion chamber of the present invention which give assurance to the operators that accidents will be safely contained within the chamber. The wall 12 and cover 43 are made of a good quality of ductile steel, such as, for example, SAE 1020 or 1030, which will distort somewhat upon impact of fragments from an exploding rotor, but will not tear or fracture. Thus, there is incorporated into the steel wall itself a certain absorptive capacity for impacts, which further adds to the safety features of the explosion chamber described herein.

It is claimed:

1. An explosion-proof enclosure for a centrifuge rotor or the like comprising a horizontal base, a circular vertical wall connected to said base and defining an enclosure for said rotor, a centrally located raised circular boss on

5 said base within said enclosure, a horizontal circular retainer plate mounted on said boss, a circular peripheral portion of said plate extending outwardly beyond the periphery of said boss, the portion of said plate extending beyond said boss being spaced apart from said base and forming a circular recess therewith, a horizontal anchor ring joined securely to the bottom of said wall, and a plurality of shear bolts securing said anchor ring to said base, an inner circular portion of said anchor ring extending partially into said circular recess, the top surface of said ring inner portion being spaced apart from the bottom surface of said retainer plate portion.

2. An explosion-proof enclosure for a centrifuge rotor or the like comprising a base, a cylindrical vertical wall attached to said base and defining an enclosure for said rotor, a retainer plate mounted on said base on the interior of said enclosure, the periphery of said plate being spaced apart from the inner surfaces of said wall, a circular portion of the bottom surface of said plate 10 20 extending from the periphery thereof being spaced apart from the top surface of said base and forming an annular recess therewith, a ring connected to the bottom of said wall and extending inwardly into the interior of said enclosure, an annular portion of said ring extending at least partially into said recess, the top surface of the portion of said ring extending into said recess being spaced apart from the bottom surface of said retainer plate, and a plurality of shear bolts securing said ring to said base.

3. An explosion-proof enclosure for a centrifuge rotor or the like comprising a base, a cylindrical vertical wall attached to said base and defining an enclosure for said rotor, first means connected to said base in the interior of said enclosure, second means in the interior of said enclosure secured firmly to the bottom of said wall, and third means releasably attaching said second means to said base, said first means horizontally overlapping said second means and being spaced apart vertically therefrom, said first means limiting the upward movement of said second means when the latter is released by said third means.

4. An explosion-proof enclosure according to claim 3 and further comprising a horizontal annular recess in the outer surface of said wall and at the upper end thereof, a cover mountable on top of said wall, an inwardly extending annular lip at the bottom of said cover, the inner peripheral edge of said lip being spaced part from the inner vertical wall of said recess, said lip and said recess being dimensioned to interlock with each other when said vertical wall is moved outwardly under the impact of objects in the interior of said enclosure.

5. An explosion-proof enclosure according to claim 3 and further comprising a horizontal annular recess in the outer surface of said wall and at the upper end thereof, a cover mountable on top of said wall, an inwardly extending annular lip on said cover, said lip having a larger diameter than said recess whereby said lip and said recess are normally disengaged when said cover rests upon said wall, said lip and said recess becoming interlocked only when at least a portion of said wall is moved outwardly under the impact of objects in the interior of said enclosure.

6. An explosion-proof enclosure for a centrifuge or the like comprising a horizontal base, a circular vertical wall attached to said base and defining an enclosure for said rotor, a horizontal circular retainer plate mounted on said base in the interior of said enclosure, a circular portion of the bottom surface of said plate extending from the periphery thereof being spaced apart from the top surface of said base and forming an annular recess therewith, a ring connected to the bottom of said wall and extending inwardly into the interior of said enclosure, 10 20 25 30 35 40 45 50 55 60 65 70 75 an annular portion of said ring extending at least partially

into said recess, a plurality of shear bolts securing said ring to said base, a horizontal annular recess in the outer surface of said wall and at the upper end thereof, a cover mountable on top of said wall, an inwardly extending annular lip at the bottom of said cover, the inner peripheral edge of said lip being spaced apart from the inner vertical wall of said recess, said lip and said recess interlocking with each other only when at least a portion of said wall is moved outwardly under the impact of objects in the interior of said enclosure.
